CLAIM

The ornamental design for a fluid control valve unit, as shown and described.

DESCRIPTION

FIG. 1 shows a front, top and right perspective view of the design;

FIG. 2 shows a back, bottom and left perspective view of the design;

FIG. 3 is an enlarged front view of a left side portion of FIG. 1;

FIG. 4 is an enlarged back view of a right side portion of FIG. 2;

FIG. 5 is an enlarged cross-section top view taken along line V-V in FIG. 3;

FIG. 6 is a cross-sectional right view taken along line VI-VI in FIG. 3; and,

FIG. 7 shows a front view of the design.

The broken lines show portions of the fluid control valve unit that form no part of the claimed design.
